UNITED STATES PATENT OFFICE.

GUSTAV ZINTER, OF BUFFALO, NEW YORK.

COASTER-BRAKE.

No. 857,855.

Specification of Letters Patent.

Patented June 25, 1907.

Application filed June 19, 1906. Serial No. 322,429.

To all whom it may concern.

Be it known that I, GUSTAV ZINTER, a citizen of the United States, residing at Buffalo, in the county of Erie and State of New York, have invented certain new and useful Improvements in Coaster-Brakes, of which the following is a specification.

This invention relates to wheel-hubs for bicycles and more particularly to hubs provided with coasting and brake-devices. As is common in devices of this kind, a forward rotation of the sprocket-wheel causes a similar rotation of the hub-barrel, while upon holding the sprocket-wheel at rest, the hub-barrel is permitted to revolve freely, and upon rotating the sprocket-wheel slightly in a reverse direction the brake is applied to prevent rotation of the hub-barrel.

The objects of my invention are the production of a wheel-hub for bicycles and the like, which is simple in construction, durable and reliable, effective and quickly responsive in action, and which is composed of very few parts; to provide a powerful brake-lever requiring an exceedingly short movement to effectively cause braking of the wheel; and to otherwise improve on back-pedaling coaster-brake hubs now in use.

To these ends the invention consists in the construction, arrangement and combination of parts to be hereinafter described and particularly pointed out in the appended claims.

In the drawings,—Figure 1 is a longitudinal section through a coaster-brake hub embodying my invention. Fig. 2 is a transverse section taken on line 2—2, Fig. 1, looking to the left. Fig. 3 is a transverse section taken on line 3—3, Fig. 1, looking to the left. Fig. 4 is a transverse section taken on line 4—4, Fig. 1, also looking to the left. Fig. 5 is a longitudinal section taken on line 5—5, Fig. 1. Fig. 6 is an elevation of the internal actuating parts removed from the hub-barrel. Fig. 7 is a detached perspective view 45 of the wedge-segment retainer. Fig. 8 is a transverse section taken on line 8—8, Fig. 1. Fig. 9 is a detached perspective view of one of the wedge-segments.

Referring to the drawings in detail, similar letters of reference refer to similar parts in the several figures.

The reference letter A indicates the lower or rear ends of the rear forks or frame members of a bicycle, in which the axle or spindle 55 B of the driving-wheel is rigidly secured in the usual manner.

C designates the hub having the usual hub-barrel or sleeve D to which the spokes of the wheel are secured. At one end of said sleeve a cup-cone or ball race E is fitted so as to revolve with said sleeve, and secured to the spindle B is a cone F having an inwardly extending portion f which is provided with a longitudinal external groove f¹. Between said cup-cone and cone F, anti-friction-balls 65 f² are interposed. Affixed to cone F, is an arm f³ which is affixed to a bracket f⁴ applied to one of the frame-members A. Threaded to the other end of the hub-barrel C is a cup-cone G comprising an internally shouldered 70 sleeve g and a flat ring g¹ held against the shoulder of said sleeve.

Mounted loosely on spindle B is a driving-sleeve H having an enlarged outer end providing an external half raceway h and an internal half raceway h¹. Interposed between cup-cone G and the external half raceway h, is a series of anti-friction balls h². Threaded onto spindle B is a cone I between which and the internal half raceway h¹ of the driving-sleeve, a series of anti-friction balls i are interposed.

Threaded onto the outer end of driving-sleeve H is the sprocket-wheel J over which the usual driving-chain (not shown) passes; a 85 nut j being applied to said driving-sleeve to prevent unscrewing of said sprocket-wheel.

By reason of the hub-sleeve receiving support on the two series of anti-friction balls f² and h², it may revolve independent of any 90 other part of the hub, and when the driving-sleeve H is held against rotation, such action takes place. In order, however, to cause forward rotation of the hub-barrel when rotating the driving-sleeve in a forward direction or to cause braking of the hub-barrel, suitable devices for co-action between the two must be provided. This I accomplish by providing the driving-sleeve with opposite or eccentric cam-surfaces K and L, as 100 clearly illustrated in Figs. 2 and 3, against which are held, respectively, propelling wedge-segments k and brake wedge segments l, having correspondingly shaped eccentric inner bearing-surfaces k¹ and l¹, respectively, and concentric outer impinging-surfaces k² and l², respectively.

The wedge-segments are arranged in pairs and are retained in proper position by a retainer-ring M, having opposite lateral extensions m at diametrically opposite points with center notches m¹ in the outer impinging-

surfaces of said segments. Said notches are of sufficient depth to permit the necessary outward and inward movement of the wedge-segments with respect to the axis of the hub, 5 so that they may impinge against surrounding parts. Said retainer-ring is split, as at N, one end thereof having a substantially circular opening n into which fits a correspondingly shaped extension n^1 formed at 10 the other end of said ring. This permits of easily applying the ring and retaining the wedge-segments in proper relation to each other and to the cam-surfaces of the driving-sleeve.

15 As shown in Figs. 1 and 5, sleeve g of the cup-cone G , is extended in rear of the ring g^1 and provides an internal impinging-surface O for segments k to act against; but if desired, said extension may be omitted and the 20 segments caused to impinge directly against the hub-barrel.

Arranged loosely within the hub-barrel and bearing against the inner end of cup-cone G is a brake-actuating sleeve P which 25 surrounds the brake-segment wedges l and is closed at its inner end. Said sleeve is reduced in diameter at its inner end to provide a shoulder p . An expandible brake-sleeve R is arranged within the hub-barrel and is fitted 30 onto the reduced end of the brake-actuating sleeve. Said brake-sleeve is provided with a longitudinal opening R^1 extending from end to end thereof, in which is located a spreading or brake-lever S having a curved 35 portion s between its ends which fits into a correspondingly formed notch r in one of the longitudinal edges of the brake-sleeve to provide a suitable fulcrum for the lever. Said lever has one end thereof arranged to enter 40 an aperture T in the brake-actuating sleeve and its other end curved at the edge, as at s^1 , at a point diagonally opposite the curved portion s ; said curved portion s^1 fitting a correspondingly shaped notch r^1 in the other 45 longitudinal edge of the brake-sleeve. The longitudinal edges of the said sleeve diverge at the end thereof adjacent the brake-actuating sleeve to allow the lever the necessary space for movement. Brake-sleeve R is held 50 against rotation by means of an ear r^2 which enter the longitudinal groove f^1 in cone F . The spindle B is securely affixed to the frame by nuts U , as is common in bicycles.

The operation of the device is as follows: 55 Driving of the wheel is effected by rotating the sprocket-wheel J in a forward direction, (noted by the arrow in Fig. 2) which by reason of its being affixed to the driving-sleeve H , causes the latter to rotate therewith and 60 force the propelling wedge-segments k outward to impinge against the surrounding shell. The eccentric surfaces k^1 on the driving-sleeve, in addition to forcing the segments k outward, retain the same in their impinging position until forward rotation of the 65

sprocket-wheel ceases, during which time the hub is compelled to rotate with the driving sleeve and sprocket-wheel. When the sprocket-wheel is held at rest, the hub may rotate independent of other parts; the rotation of the hub causing propelling wedge-segments to recede or ride down the eccentric or cam-surfaces of the driving-sleeve; thereby permitting the hub to run entirely free on the roller-bearings. In order to apply the 70 brake, the sprocket-wheel is rotated rearward, (as noted by the arrow in Fig. 3,) which causes the driving-sleeve H to rotate therewith. By reason of the cam or eccentric surfaces L on said sleeve and the co-acting brake 75 wedge-segments being arranged reversely to surfaces K and wedge-segments k , the wedge-segments l are forced against the inner face of the brake-actuating sleeve P and cause the same to revolve momentarily with the driving-sleeve and independent of the hub-barrel. 80 A slight reverse or rearward rotation of the brake actuating-sleeve, which normally is held against turning by reason of its connection with the brake-sleeve, causes the spreading or brake-lever S to be actuated, which in turn causes spreading or expanding of the brake-sleeve against the surrounding hub-barrel. The extent of the braking action being of course in accordance with the rearward 85 pressure exerted on the driving-sleeve. 90

By means of the construction described, the extent of reverse or rearward rotation of the sprocket-wheel required to set the brake is reduced to a minimum, a positive gripping-action is obtained between the wedge-segments and surrounding parts on rotation of the sprocket-wheel, and a free running of the hub with the least possible resistance is assured when the sprocket-wheel is set at rest 95 after the parts have been rotated in a forward direction.

It is within the province of my invention to make changes in the form, shape and construction of parts without departing from the spirit thereof or sacrificing any advantages, and it is therefore desired that the claims be given the broadest interpretation permissible by the prior art.

Where in the claims, the term "hub-barrel" is employed, it is to be understood as covering and having reference to the hub-barrel proper, or a hub-barrel with a part or parts attached thereto.

Having thus described my invention, what 120 I claim is,—

1. The combination with the hub-barrel and a spindle fixedly supported, of a driving-member rotatable on said spindle and having opposite eccentric surfaces, an interior brake-device, and propelling and brake wedge-segments co-acting with said eccentric surfaces and adapted to impinge respectively against the surrounding hub-barrel and against said 125 brake-device.

2. The combination with the hub-barrel and a spindle fixedly supported, of a driving-sleeve rotatable on said spindle and having opposite eccentric surfaces, an interior brake-device, propelling wedge-segments and brake wedge-segments co-acting with said eccentric surfaces and adapted to impinge respectively against the interior of the hub-barrel and against the brake-device, and means for retaining said wedge-segments in operative position.
3. The combination with the hub-barrel and a spindle fixedly supported, of a driving-sleeve rotatable on said spindle and having opposite eccentric surfaces, an interior brake-device, propelling wedge-segments and brake wedge-segments co-acting with said eccentric surfaces and adapted to impinge respectively against the interior of the hub-barrel and against the brake-device, each of said wedge-segments having its outer surface notched, and a retaining-ring having lateral extensions entering the notches in said wedge-segments.
4. The combination with the hub-barrel and a spindle fixedly supported, of a driving-sleeve between the two and rotatable on said spindle, said sleeve having two pair of opposite eccentric surfaces, two pair of oppositely positioned wedge-segments having corresponding inner eccentric bearing surfaces and concentric outer impinging surfaces, one pair of said segments being adapted to impinge against the surrounding hub-barrel, and an interior brake-device against which the other pair of said segments is adapted to impinge.
5. The combination with the hub-barrel and a spindle fixedly supported, of a driving-sleeve between the two and rotatable on said spindle, said sleeve having two pair of opposite eccentric surfaces, two pair of oppositely positioned wedge-segments having corresponding inner eccentric bearing surfaces and concentric outer impinging surfaces provided each with a notch, a retainer-ring between the two pair of wedges provided with lateral extensions fitting the notches in said segments, and an interior brake-device against which one pair of said segments is adapted to impinge to cause actuation thereof, the other pair of segments being adapted to impinge against the surrounding barrel-hub.
6. The combination with the hub-barrel and a spindle fixedly supported, of a driving-sleeve rotatable on said spindle and having two pair of opposite eccentric surfaces, two pair of wedge-segments co-acting with said eccentric surfaces and having notches in their outer surfaces, a split-retainer ring having opposite lateral extensions fitting the notches in said segments and having at one end a circular opening and at its other end a correspondingly shaped projection fitting said opening, and a brake-device within the hub-barrel adapted to be actuated by one pair of said segments, and the other pair of said segments being adapted to impinge against the hub-barrel.
7. The combination with the hub-barrel and a spindle fixedly supported, of a driving-sleeve between the two and rotatable on said spindle, means to cause the hub-barrel to rotate in a forward direction on forward rotation of said driving-sleeve, a longitudinally split brake-sleeve within the hub-barrel, a spreading-lever located between the longitudinal edges of said brake-sleeve, and means for actuating said lever on reverse rotation of the driving-sleeve.
8. The combination with the hub-barrel and a spindle fixedly supported, of a driving-sleeve between the two and rotatable on said spindle, means to cause the hub-barrel to rotate in a forward direction on forward rotation of the driving-sleeve, a longitudinally split brake-sleeve held against rotation within the hub-barrel, a spreading-lever between the longitudinal edges of said brake-sleeve, a brake-actuating sleeve capable of limited rotation and co-operating with said spreading-lever, and a device between the driving-sleeve and the brake-actuating sleeve for causing rotation of the latter to actuate said spreading-lever.
9. The combination with the hub-barrel and a spindle fixedly supported, of a driving-sleeve between the two and rotatable on said spindle, means to cause the hub-barrel to rotate in a forward direction on forward rotation of the driving-sleeve, a longitudinally split brake-sleeve held against rotation within the hub-barrel and having one of its longitudinal edges provided with a curved notch, a spreading-lever between the longitudinal edges of the brake-sleeve provided with a curved extension fitting said notch, a brake-actuating sleeve capable of limited rotation and co-operating with said spreading-lever, and a device between the driving-sleeve and the brake-actuating sleeve for causing rotation of the latter to actuate said spreading-lever.
10. The combination with the hub-barrel and a spindle fixedly supported, of a driving-sleeve between the two and rotatable on said spindle, means to cause the hub-barrel to rotate in a forward direction on forward rotation of the driving-sleeve, a longitudinally split brake-sleeve held against rotation within the hub-barrel and having each of its longitudinal edges provided with a curved notch, said notches being at different points in the length of the sleeve, a spreading-lever between the longitudinal edges of said brake-sleeve and having curved extensions fitting said notches, a brake-actuating sleeve capable of limited rotation and co-operating with said spreading-lever, and a device between the driving-sleeve and the brake-actuating sleeve.

sleeve for causing rotation of the latter to actuate said spreading-lever.

11. The combination with the hub-barrel and a spindle fixedly supported, of a cone held against rotation on the spindle near one end thereof and having an extension provided with a longitudinal groove, a driving-sleeve near the other end of the spindle and rotatable thereon, means to cause the hub-barrel to rotate in a forward direction on forward rotation of the driving-sleeve, a longitudinally-split brake-sleeve having an inwardly directed ear at one end fitting into the longitudinal groove of said cone-extension, and means to spread the brake-sleeve on reverse movement of the driving-sleeve.

12. The combination with the hub-barrel and a spindle fixedly supported, of a driving-sleeve between the two and rotatable on said spindle, means to cause the hub-barrel to rotate in a forward direction on forward rotation of the driving-sleeve, a longitudinally split brake-sleeve held against rotation within the hub-barrel, a spreading-lever between the longitudinal edges of said brake-sleeve a

brake-actuating sleeve having one end closed and provided with an aperture in said end into which said spreading-lever fits, and a device between the driving-sleeve and the brake-actuating sleeve for causing rotation of the latter to actuate said spreading-lever.

13. The combination with the hub-barrel and a spindle fixedly supported, a brake-device adapted to act against the inner surface of said hub-barrel and comprising a braking-element, a brake actuating-sleeve operatively connected with said braking-element, a sleeve on said spindle having eccentric surfaces, and wedge segments coacting with said eccentric surfaces and adapted to be driven against the inner surface of said brake actuating-sleeve when rotating said spindle in a rearward direction.

In testimony whereof, I have affixed my signature in the presence of two subscribing witnesses.

GUSTAV ZINTER.
